(57) CLAIM

The ornamental design for a security yard sign with words of a telecommunications company and an alarm company, as shown and described.

DESCRIPTION

FIG. 1 is a perspective front view of the security yard sign with words of a telecommunications company and an alarm company;

FIG. 2 is a front elevation view thereof;

FIG. 3 is a rear elevation view thereof;

FIG. 4 is a left side elevation view, the right side being a mirror image thereof; and,

FIG. 5 is a top elevation view, the bottom view being a mirror image thereof.

The broken line showing of a yard stake is included for the purpose of illustrating portions of the “article” and forms no part of the claimed design.
